UNITED STATES PATENT OFFICE

2,515,101

MACHINE FOR CONDITIONING SHRIMP

Reginald K. Swinden, Houston, Tex.

Application January 19, 1946, Serial No. 642,349

11 Claims. (Cl. 17—3)

1

This invention relates to a machine for conditioning shrimp.

An object of the invention is to provide a machine of the character described specially designed for removing the alimentary canal, known as the sand string, from shrimp.

It is a further object of the invention to provide, in a machine of the character described, means for removing said sand string without injuring or mutilating the shrimp.

A still further object of the invention is to provide, in a machine of the character described, a special type of cutter disc assembly which will remove the sand string with the loss of a minimum edible portion of the shrimp.

The invention further comprehends means for constantly cleansing the cutter disc assembly.

A still further object of the invention is to provide a machine of the character described which is automatic in its operation.

With the above and other objects in view the invention has particular relation to certain novel features of construction, operation and arrangement of parts, an example of which is given in this specification and illustrated in the accompanying drawings; wherein—

Figure 1 is a plan view of the machine, partly in section.

Figure 2 is a vertical, sectional view.

Figure 3 is an end view, partly broken away.

Figure 4 is a transverse, sectional view, partly broken away.

Figure 5 is an enlarged, fragmentary end view shown partly in section.

Figure 6 is an enlarged, fragmentary, longitudinal sectional view taken on the line 6—6 of Figure 5.

Figure 7 is an enlarged, side elevation, partly in section, of the disc cleaner.

Figure 8 is a plan view thereof.

Figure 9 is a cross-sectional view thereof taken on the line 9—9 of Figure 7.

Figure 10 is an enlarged, elevational view of a clamp employed showing the shrimp mounted therein.

Figure 11 is an enlarged, fragmentary, sectional view thereof taken on the line 11—11 of Figure 10.

Figure 12 is an enlarged, fragmentary plan view of the clamp.

Figure 13 is a cross-sectional view thereof taken on the line 13—13 of Figure 10.

Figure 14 is a cross-sectional view of the conditioned shrimp; and,

Figure 15 is a top plan view of the machine.

Referring now more particularly to the draw-

2

ings wherein like numerals of reference designate the same parts in each of the figures, the numeral 1 designates a suitable base, secured to and upstanding from which are the side supporting standards 2 which are spaced apart.

There is a transverse, tubular, supporting spindle 3 whose ends are fixed in said standards, and suitably secured therein, as shown in Figure 4.

Rotatably mounted on said spindle there is a hub 4, one end of which abuts an external annular shoulder 5 on the spindle and whose other end abuts a ring 6 around the spindle and secured thereon by a set screw 7.

Fixed to the hub 4 and extending outwardly therefrom in parallel relation with the spindle are the spokes 8 and fixed on the outer ends of these spokes there is a sprocket wheel 9.

In the present illustration a line shaft 10 is provided which may be rotated from any suitable source of power, and fixed on this shaft there is a sprocket wheel 11 aligned with the sprocket wheel 9 and a sprocket chain 12 operates over these sprocket wheels and transmits rotation from the sprocket wheel 11 to the sprocket wheel 9 and to the hub 4.

Also fixed on the hub 4 are the radiating spokes 13 whose outer ends carry clamps, each clamp comprising the jaws 14 and 15. The spokes 13 are tubular and threaded onto their outer ends are the caps 16 whose outer ends are formed with the pairs of spaced lugs 17, 17, said pairs being spaced apart and the lugs of each pair being also spaced apart. The clamp jaws 14, 15 are fastened to similar base plates 18, 18, in any approved manner, preferably by set screws 19, 19 and these respective plates are formed with hinge members 20, 20 which are fitted between the lugs 17 of the respective pair and hinge pins 21, 21 are fitted through each pair of lugs 17 and 40 through the corresponding hinge members 20 whereby the clamp jaws 14, 15 are pivotally mounted on the outer ends of said spokes.

Each cap 16 has a central bearing 22 and there is a jaw actuating rod 23 which works through each bearing into the corresponding spoke and whose inner end has a nut 24 threaded thereon.

A coil spring 25 surrounds each rod 23 and is interposed between the cap 16 and the nut 24.

The pressure of said spring may be regulated by adjusting the nut 24 on the rod 23 and said adjustment may be maintained by the lock nut 26 also threaded onto the rod 23.

The outer end of each rod 23 has oppositely disposed notches 27, 27 and the hinge members 20 have inwardly extended arms 28, 28 whose

free ends extend into said notches. The outer end of each rod 23 is reduced and fitted on said reduced end there is a washer 29 which is pinned thereon by the pin 30 so as to limit the inward movement of the rod 23. The pressure of the spring 25 normally holds the clamp jaws 14, 15 in clamping position, as shown in Figures 11 and 12.

The inner side of each jaw 15 has an arcuate row of supporting fingers 31, as clearly shown in Figures 10, 11 and 12 to support the shrimp, as hereinafter explained, and also has an inwardly extended stop 32 against which the large end of the shrimp rests when the shrimp is positioned in the clamp.

It will be noted from an inspection of Figure 12 that the space between the clamp jaws 14 and 15 slightly widens forwardly so as to better conform to the contour of the shrimp held in the clamp.

Between the clamps are the arcuate tracks 33 with their concaved sides outwardly. The ends of these tracks are secured to the corresponding caps 16 and their outer surfaces merge in the outer surfaces of the corresponding clamp jaws 14 so that said outer surfaces of said jaws form, in effect, continuation of said tracks. The mid-portion of the tracks 33 are supported on the hub 4 by the supporting blocks 34 which may be attached to the tracks by suitable set screws, as shown in Figure 2.

Fastened to the inner side of the upper end of one of the standards 2 there is a cam member 35 which is flared outwardly and whose inner face is formed with a cam shaped groove 36 and fastened on the inner side of the lower end of said last mentioned standard 2 there is a cam member 37 whose inner face is formed with a cam shaped groove 38.

Each clamp jaw 14 has an arm 39 secured thereto which extends diagonally outwardly therefrom and on whose outer end there is mounted a roller bearing 40.

The hub 4 with its radiating spokes 13 and the clamp members thereon and the tracks between said clamp members form a rotary unit and as said unit rotates the roller bearings 40 successively move through the grooves 36 and 38 and the corresponding arms 39 are depressed or moved inwardly causing a corresponding outward movement of the corresponding jaws 14 so that said jaws will be swung to open position, thus causing an outward movement of the corresponding rod 23 which in turn will cause the opposing jaw 15 to swing open. This simultaneous movement of the jaws 14 and 15 is caused by the arms 28 which project into the notches 27 of the corresponding rod 23, the corresponding spring 25 being placed under compression. As the bearings 40 pass the cam grooves 36, 38 the jaws which have been open will be moved to closed position by the expansion of the corresponding springs 25. The jaws are shown in open position to receive a shrimp in Figure 1 and in open position to discharge the shrimp, as shown in Figure 4. The entrant ends of the cam grooves are slightly flared so as to insure the entrance of the roller bearings into said grooves.

Pivotedly mounted on the base 1 there is a relatively wide, supplemental frame 41 and mounted on the upper end of this frame there is an electric motor 42 having an extended shaft 43. Opposite the motor 42 on the supplemental frame 41 there is a bearing 44 extending through which there is a bushing 45 which is maintained in place by a set screw 46. The inner end of this bushing is enlarged forming an annular shoulder

which abuts the inner side of the bearing 44 and the inner end of the bushing 45 is formed into a disc-like plate 47 to the inner side of which the annular hub 48 is secured and said bushing has a reduced extension, extending inwardly from said plate through said hub.

Rotatably mounted on the hub 48 there is a rim 49 whose outer surface may, if desired, be formed of rubber. This rotatable rim is confined between the margin of the plate 47 and an external annular shoulder on the hub 48. The shaft 43 extends axially through, and rotates in, the bushing 45.

Keyed on the shaft 43, between the hub 48 and the motor 42 there is a cutter disc assembly. This assembly comprises the end guide discs 50, 50, the disc-like cutters 51, 51, between the discs 50 and the ejector disc 52 between the disc-like cutters. This assembly is clamped together by the screws 53.

As will be noted from an inspection of Figure 5, the margins of the discs 50 converge so as to guide the shrimp with respect to the disc-like cutters and the margins of the cutters terminate in sharp cutting edges which extend out beyond the margins of the discs 50 and the margins of the cutters are preferably beveled inwardly. The ejector disc is of slightly less transverse diameter than that of the cutters and its margin is formed with forwardly pitched teeth 54. The disc-like cutters 51, 51 are spaced apart a sufficient distance to make an incision on each side of the sand string, or alimentary canal, of the shrimp of the required depth and the teeth of the disc 52 will eject the same as the cut is made.

It is desirable that provision be made for cleansing the cutters as the work progresses. For that reason a bracket 55 is secured to the upper side of the supplemental frame 41 and the upper end of this bracket is formed into an outwardly curved guard 56 which partially surrounds and is spaced from the cutter disc assembly. There is a cleaning device inserted through the guard 56 which comprises a water container 57 and opposed elongated jaws 58, 58 which are hinged thereto. The inner ends of these jaws are arcuate to conform to the curvature of the cutter discs 51. These arcuate ends are externally beveled, as at 59, to wedge against the tapering margins of the discs 52. These jaws are provided with a longitudinal slot 60 which extends through both of the jaws and fitted tightly in said slot 60 there is felt 61 whose outer end has a V-notch 62 to fit closely over the beveled margins of the cutter discs 51, 51, as illustrated in Figures 6 and 8. The container 57 is kept supplied with water and is provided with a small duct 63 so as to allow the water supplied to the felt to keep it moist. A plug 64 is inserted into the outer end of the container 57 and is provided with a small duct 65 to prevent the formation of a vacuum in the container 57. This moist felt will clean the disc-like cutters of all foreign matter as the cutters rotate and the cleaning assembly is fitted tightly through the guard 56 but may be adjusted inwardly from time to time to take up for wear so that the felt will, at all times, be in firm contact with the cutter discs. The guard 56 also prevents the cutter assembly from throwing material outwardly as the cutter assembly rapidly rotates but said material will pass downwardly through the passageway 66 provided for it.

The rotatable rim 49 is held in constant contact with the tracks 33 and with the outer surfaces of the jaws 14 by a pull spring 67, as shown in Figure 2.

This pull spring is attached, at one end, to the base 1 and at its other end to the underside of the supplemental frame 41. This spring not only holds the rotatable rim 49 against said tracks but steadies the movement of the same and prevents it from falling outwardly.

Fastened to the inner sides of the standards 2 are the transversely aligned arms 68, 68 which extend diagonally upwardly, and mounted to rotate the free ends of these arms there is a transverse shaft 69, one end of which extends beyond its corresponding arm. Depending from the extended end of said shaft there is an arm 70. A coil pull spring 71 is attached, at one end, to said arm 70 and at its other end to the corresponding standard 2.

Depending from the shaft 69 are the spaced arms 72, 72. There is a positioning roller 73 having end pintles which rotate in bearings in the free ends of the arms 72. This roller has a central groove 74 around it which is in alignment with the groove in the cutter assembly formed by the beveling of the discs 50. This roller is provided to accurately position the shrimp in the clamps so that they will accurately align with the cutter disc assembly.

In operation the unit mounted on the hub 4 will rotate with said hub. As the roller bearings 40 come into contact, successively, with the cam member 35 the corresponding clamp jaws 14, 15 will be opened, as hereinabove explained, and a shrimp, as 75, may be placed therein, resting on the fingers 31. The head of the shrimp will first have been removed and the head end of the shrimp will rest against stop 32, shown in Figure 12. When the roller bearing 40 passes the cam member 35 said clamp jaws will be closed by the operation of the spring 25, shown in Figure 11, and will firmly clamp the shrimp but not with sufficient violence to mutilate, or bruise, the shrimp. As the shrimp passes the positioning roller the outer portion of the shrimp will pass through the groove 74 and if the shrimp is not perfectly aligned with the cutter discs the positioning roller will align it therewith. As the shrimp comes into contact with the cutting discs the alimentary canal, as 76, thereof will be aligned between the cutting discs and said discs will make an incision on each side of said sand string throughout the length of the shrimp and the ejector disc 52 will remove said sand string and the same will pass through the passageway 66 and fall onto the base 1 or into a suitable receptacle provided to receive it.

As hereinbefore stated the outer margins of the discs 50, 50 converge and, as shown in Figure 5, at their outer sides they have outwardly extended rims. These are provided to prevent the particles of the matter being ejected from being thrown out laterally onto the rim 49, but will direct said particles tangentially downwardly.

The conditioned shrimp will be carried on around until the bearing roller 40 contacts the cam member 37 whereupon the jaws 14, 15 will be opened, as shown in Figure 4, and the shrimp will be discharged through the chute 77, as shown in Figures 2 and 4, into a suitable receptacle provided for the purpose.

The drawings and description disclose what is now considered to be a preferred form of the invention, by way of illustration only, and not by way of limitation, while the broad principle of the invention will be defined by the appended claims.

What I claim is:

1. In a machine for conditioning shrimp; a rotatable cutter unit embodying spaced disc-like cutters, a cleaner for the cutters including a container for liquid, jaws at one end of the container which embrace the margins of the cutters, and an absorbent material in the jaws positioned to frictionally engage the outside of the cutters, said container having an air inlet and a duct through which the liquid therein may flow to said absorbent material to saturate the same.

2. In a machine for conditioning shrimp; a cutter unit embodying two disc-like cutters spaced apart, a support on which the cutter unit is mounted, a bracket on said support, a cleaning element adjustably mounted on the bracket and including a container, jaws hinged to one end of the container and arranged to embrace the cutter margins, and a soft absorbent material in the jaws in contact with the outer sides of the margins of the cutters, said container having a duct through which a cleansing fluid may flow therefrom to said material and also having an air inlet into the container.

3. In a machine for conditioning shrimp; a support, a rotatable cutter unit on the support embodying spaced discs whose margins converge inwardly, disc-like cutters between said discs and spaced apart, and a cleaner for the cutters on the support and having means at one end which wedge between the margins of said discs and embrace the margins of the cutters, said means including absorbent material positioned to frictionally engage the outside of the cutter margins and means for supplying a cleansing fluid to said material to keep the same saturated.

4. A machine for conditioning shrimp, comprising, a supporting frame, a rotatable assembly on the frame including clamp means having jaws which are spaced apart and are provided with inside, opposed, plain faces which are adapted to receive and clamp a shrimp, shrimp supporting means on the clamp means, which are spaced apart, cutters spaced apart and arranged to co-act with said assembly as the latter rotates to form longitudinal incisions, spaced apart, along the outer side of the shrimp, ejector means between the cutters arranged to remove that portion of the shrimp between the incisions and means for thereafter releasing the clamp means from the shrimp to permit discharge of the conditioned shrimp.

5. A machine for conditioning shrimp comprising, a supporting frame, a rotatable assembly on the frame including clamp means adapted to receive and clamp shrimp, shrimp supporting means on the clamp means, spaced rotatable, disc-like cutters arranged to co-act with said clamp means, as the assembly rotates, to form longitudinal incisions, spaced apart, along the shrimp and disc-shaped means on opposite sides of, and rotatable with, said cutters and spaced laterally therefrom adapted to guide the shrimp, which are in the clamp means, relative to the cutters.

6. A machine for conditioning shrimp comprising, a support, a rotatable assembly on the support including a plurality of radially extended pairs of jaws forming clamps adapted to receive and clamp shrimp and tracks forming guides between the clamps, the jaws on one side of the assembly, when in clamping position aligning with and merging into adjacent guides, cutters spaced apart and arranged to co-act, successively, with said clamps, as the assembly rotates, to form longitudinal incisions, spaced apart, along the

shrimp, and a roller associated with the cutters and movable along said guides and around said jaws to maintain the cutters in co-acting relation with the clamps as said assembly rotates.

7. A machine for conditioning shrimp comprising, a support, a rotatable assembly on the support including a plurality of clamps adapted to receive and clamp shrimp and tracks forming guides between the clamps, each clamp being formed of two opposing jaws having opposed, spaced, clamp faces, cutters spaced apart and arranged to co-act, successively, with said clamps, as the assembly rotates, to form longitudinal incisions, spaced apart, along the shrimp, a roller associated with the cutters and movable along said guides and around the corresponding jaws to maintain the cutters in co-acting relation with the clamps as said assembly rotates, and means between the cutters arranged to disintegrate that portion of the shrimp between the incisions for ejection.

8. A machine for conditioning shrimp comprising, a support, a rotatable assembly on the support including a plurality of clamps, each clamp being formed of spaced jaws, adapted to receive and clamp shrimp between said jaws and tracks between the clamps and merging into corresponding jaws thus forming a continuous guide, cutters spaced apart and arranged to co-act, successively, with said clamps, as the assembly rotates, to form longitudinal incisions, spaced apart, along the shrimp, a roller associated with the cutters and movable along said guide to maintain the cutters in co-acting relation with the clamps as said assembly rotates, and means arranged to successively co-act with said clamp means and effective to cause said jaws to release the conditioned shrimp.

9. A machine of the character described comprising, a supporting structure, an assembly movable thereon and including a holder formed with confronting clamp faces to clamp the sides of a shrimp, an arcuate row of spaced projections extending from one face toward the other face and spaced inwardly from the outer margin of the

5
10
15
20
25
30
35
40
45

holder to support the shrimp, spaced cutting means on said structure arranged to make longitudinal incisions in a shrimp in the holder on opposite sides of the sand string of the shrimp as the holder moves into co-acting relation with the cutters, and means associated with the cutters for removing the sand string from between said incisions.

10. In a machine for conditioning shrimp, a support, a rotatable assembly mounted on the support, a clamp on said assembly including opposed jaws having outer margins that are curved outwardly to substantially conform to the contour of a headless shrimp, said jaws having inside, plain clamping faces adapted to clamp the sides of the shrimp, an arcuate row of supporting projections on one of the jaws and extending across the space between said faces and spaced inwardly from the outer margins of the jaws to support the inner side of the shrimp.

11. In a machine for conditioning shrimp, a rotatable cutter assembly comprising circular guide discs, a pair of disc-like cutters between said discs and a spacer between said cutters to space the cutters apart, the margins of the discs converging inwardly to the cutters to guide the shrimp with respect to said cutters, said cutters terminating in sharp cutting edges which extend out beyond the margins of the discs.

REGINALD K. SWINDEN.
